UNITED STATES PATENT OFFICE.

RAYMOND LESTER, OF JACKSONVILLE, FLORIDA.

PEDESTAL FOR RAILWAY ROLLING STOCK.

Application filed October 25, 1922. Serial No. 596,793.

To all whom it may concern:

Be it known that I, RAYMOND LESTER, a citizen of the United States, residing at Jacksonville, in the county of Duval and State of Florida, have invented certain new and useful Improvements in Pedestals for Railway Rolling Stock, of which the following is a specification.

This invention relates to improvements in pedestals for railway rolling stock.

An object of the invention is to provide wear plates insertable in the jaws or legs of the pedestal to engage the journal box and prevent frictional contact of the latter with the pedestal.

A more important object of the present invention is the provision of novel means for attaching the wear plates to the pedestals through the medium of which said plates are held securely to the pedestal, yet permitting quick removal of the plates when desired.

Co-ordinate objects of the invention will be apparent from the following description of the form of invention illustrated in the accompanying drawings wherein:—

Fig. 1 is an elevational view of a pedestal constructed in accordance with this invention;

Fig. 2 is a vertical sectional view of the same taken on the line 2—2 of Fig. 1; and

Fig. 3 is a horizontal sectional view taken on the line 3—3 of Fig. 2 looking in the direction of the arrow.

A pedestal frame or body 4 of substantially standard construction is illustrated in the drawings. This frame includes parallelly arranged legs 5 which are adapted to embrace a journal box in a manner well known in the art. Each of the legs 5 is of multipart construction, the inner face of each of which parts is recessed as indicated at 6. The upper and lower wall of each of said recesses is of semi-circular configuration as indicated at 7. The outer wall of each part of each of said pedestal legs is formed to provide nut receiving depressions or recesses 8.

The wear receiving plates constructed in accordance with this invention, designated at 9, are each of oblong configuration and are equipped with terminal semi-circular projections 10 so as to complement the recesses 6 in which said plates 9 are mounted. The thickness of each plate 9 is in excess of

the depth of the recess 6 in which it is mounted so that the outer face of the plate will be remote from the inner face of the pedestal leg as shown to advantage in Fig. 1.

In order to secure the wear plates to the pedestal legs, suitable means is provided which in the present instance consists of bolts 11 the heads 12 of which are cast in the wear plates 9. The shanks of the bolts project through corresponding openings in each of the parts of each pedestal leg and terminate in the recesses 8. The free terminals of said shanks are threaded and are detachably engaged by nuts 13. In view of the recesses 8 the nuts 13 may be engaged with and disengaged from the shanks of the bolts 11 with facility and expediency.

Upon reference to Fig. 2 of the drawings it will be noted that the outer marginal edges 14 of the wear plates 9 extend appreciably beyond the outer faces of each pedestal leg so as to provide a protective lip overhanging the exposed edges of the pedestal legs to prevent wear on said edges. It is apparent that the construction of pedestal herein recited permits contact of the wear plates with the journal boxes thereby taking up all wear from the pedestal legs. These wear plates will last for a considerable period of time but their manner of association with the pedestal legs, as above described, permits them to be removed and replaced at a relatively low cost so as to make the pedestals usable for an indefinite period of time.

It is of course to be understood that various changes may be made in this device within the scope of the appended claims. However, it is important that the wear plates be detachable and it is important that they be associated with the pedestal legs in a manner which permits attachment and detachment of the plates with facility and expediency. By casting the bolts in the wear plates an inexpensive durable structure is provided which positively unites the bolts to the plates with obvious desirable results. Moreover, by equipping the ends of the wear plates with semi-circular enlargements which engage corresponding recesses in the pedestal legs, lateral displacement of the wear plates is positively eliminated.

What is claimed is:—

1. A pedestal for rolling stock including legs having plate receiving recesses on their

inner faces, and wear plates mounted in the recesses of said legs each of which is equipped with cast in threaded shanks engageable through said legs, and nuts mounted on said shanks.

2. A pedestal for railway rolling stock, in combination with multipart parallelly ar-

ranged legs, a wear plate engageable in each part of each pedestal leg comprising an oblong body the ends of which issue into enlargements engageable in corresponding recesses in the pedestal leg, and means to secure said plates from displacement.

RAYMOND LESTER.
